US00D647206S

(12) **United States Design Patent**
Massad

(10) **Patent No.:** US D647,206 S
(45) **Date of Patent:** ** Oct. 18, 2011

(54) **SLENDER PIN RECEIVER FOR A JAW
RELATION RECORDING DEVICE**

6,152,730 A 11/2000 Wildman
D459,806 S * 7/2002 Webb D24/150
D459,807 S * 7/2002 Webb D24/150

(75) Inventor: **Joseph J. Massad**, Tulsa, OK (US)

(Continued)

(73) Assignee: **Global Dental Impression Trays, Inc.**,
Tulsa, OK (US)

FOREIGN PATENT DOCUMENTS

EP 0950384 10/1999

(**) Term: **14 Years**

Primary Examiner — Bridget L Eland

(21) Appl. No.: **29/382,237**

(74) Attorney, Agent, or Firm — Head, Johnson & Kachigan,
P.C.

(22) Filed: **Dec. 30, 2010**

(57) **CLAIM**

(51) **LOC (9) Cl.** 24-02

The ornamental design for a slender pin receiver for a jaw
relation recording device, as shown and described.

(52) **U.S. Cl.** D24/181; D24/140

DESCRIPTION

(58) **Field of Classification Search** D24/140,
D24/152, 156, 180, 181; 433/68, 69, 213,
433/214

FIG. 1 is a top perspective view of a first embodiment of a
slender pin receiver for a jaw relation recording device showing
my new design;

See application file for complete search history.

FIG. 2 is a top view of FIG. 1;
FIG. 3 is a side view of FIG. 1;
FIG. 4 is a bottom view of FIG. 1;
FIG. 5 is a front view of FIG. 1;
FIG. 6 is a rear view of FIG. 1;

FIG. 7 is a cross-sectional view along line 7-7 of the slender

pin receiver for a jaw relation recording device shown in FIG.

2;

FIG. 8 is a top perspective view of a second embodiment of a

slender pin receiver for a jaw relation recording device showing

my new design;

FIG. 9 is a top view of FIG. 8;

FIG. 10 is a side view of FIG. 8;

FIG. 11 is a bottom view of FIG. 8;

FIG. 12 is a front view of FIG. 8;

FIG. 13 is a rear view of FIG. 8; and,

FIG. 14 is a cross-sectional view along line 14-14 of the

slender pin receiver for a jaw relation recording device shown

in FIG. 9.
